C. CHRISTIANSEN,
TOOL RETAINER FOR PERCUSSIVE HAMMERS,
APPLICATION FILED JULY 7, 1915.

1,176,343.

Patented May 21, 1919.

Inventor,
Charles Christiansen,
By Henry W. Johnson actg.

UNITED STATES PATENT OFFICE.

CHARLES CHRISTIANSEN, OF GELSENKIRCHEN, GERMANY

TOOL-RETAINER FOR PERCUSSIVE HAMMERS.

1,176,343.

Specification of Letters Patent. Patented Mar. 21, 1916.

Application filed July 7, 1915. Serial No. 38,402.

To all whom it may concern:

Be it known that I, CHARLES CHRISTIANSEN, a subject of the King of Prussia, residing at Gelsenkirchen, in the Kingdom of Prussia, German Empire, have invented certain new and useful Improvements in Tool-Retainers for Percussive Hammers; and I do hereby declare the following to be a full, clear, and exact description of the invention, 10 such as will enable others skilled in the art to which it appertains to make and use the same, reference being had to the accompanying drawings, and to letters or figures of reference marked thereon, which form a part 15 of this specification.

My invention relates to improvements in rock drills and the like, and more particularly in rock drills, in which the stem of the drill steel is connected with the cylinder or 20 body of the tool by means of a retainer in the form of a coiled spring secured at one end to the cylinder or body and embracing at its opposite end the steel and tending to hold the same in position and assisting in retracting 25 the same from the bore hole in case the steel should stick therein.

The object of the improvements is to provide a tool of this class in which the steel and spring can readily be attached to the 30 body of the tool.

With this and other objects in view my invention consists in the matters to be described hereinafter and particularly pointed out in the appended claims.

35 For the purpose of explaining the invention an example embodying the same has been shown in the accompanying drawing, in which the same letters of reference have been used in all the views to indicate corresponding parts.

In said drawing—Figure 1, is a side view of the spring used as a steel retainer, Fig. 2, is a similar plan view showing the spring attached to the tool and holding the steel in 45 position, Fig. 3, is a perspective view showing the rocking clamping member of the spring which embraces the stem of the steel, and Fig. 4, is a similar perspective view showing the spring and its eyes provided for 50 attaching the rocking clamping member.

In the example shown in the drawing the body or cylinder *h* of the tool, which may be a pneumatic tool, is formed at its outer end with screw-threads which are engaged by the 55 coils of a coiled spring *a*. The latter is

formed at its outer end with two eyes *b* and *b'* located diametrically opposite each other, one of the said eyes being formed by forming the spring at one side in the form of a circular loop *b* and the other eye being 60 formed by bending the end of the wire into circular form, as is best shown in the perspective view shown in Fig. 4. The said eyes provide a pivotal support for a bail by means of which the steel *e* is held in position. 65 As shown the said bail consists of an outer part *c'* which is substantially in the form of the letter U, two branches *c²* which are bent at acute angles from the branches of the part *c'*, and outwardly projecting arms which 70 provide the pivots for the bail and are inserted in the eyes *b* and *b'* of the spring, as is shown in Figs. 1 and 2. When thus attached to the spring *a*, the bail provides a means for retaining the steel *e* on the cylinder of the tool, which steel is formed with a flange or collar *f* provided for engagement with the U-shaped part *c'* of the bail. 75

In the practical use of the tool, the spring is screwed onto the cylinder and into the 80 position shown in Fig. 2. Thereupon the bail *c'*, *c²*, *c³* is rocked into the position shown in Fig. 1, whereupon the steel can be inserted through the spring and into the cylinder. After the steel has thus been 85 brought into position, the bail is rocked into the position shown in Fig. 2 in which it engages the steel above the flange *f*. In a similar way the spring can be attached to the cylinder when the drill steel is in position, 90 as may be necessary for retracting the steel from the bore hole when using the drill with the spring removed.

In the preferred form of the bail shown in Fig. 3 the U-shaped part is narrower at 95 the ends *g* of the branches *c'*, so that it is spread apart when rocking the same into engagement with the stem of the steel and is thereafter clamped together by spring action and loosely embraces the stem so as to 100 permit free play of the steel. Thereby the bail is locked in engagement with the steel and can not be rocked into the inoperative position shown in Fig. 1 by the percussions caused by the operation of the drill. 105

I claim herein as my invention:

1. In a rock drill, the combination with the body of the tool, and the drill steel guided within said body, of a coiled spring concentrically secured to said body, and a 110

rocking member on said spring adapted to be rocked into and out of locking engagement with the drill steel.

2. In a rock drill, the combination with the body of the tool, and the drill steel guided within said body and having a flange, of a coiled spring concentrically secured to said body, a rocking bail on said spring adapted to be rocked into and out of locking and retracting engagement with the drill tool and its flange.

3. In a rock drill, the combination with the body of the tool, and the drill steel guided within said body and having a flange, of a coiled spring concentrically secured to said body and bent at its end into two diametrically opposite eyes, and a bail pivotally mounted in said eyes and adapted to be rocked into and out of locking and retracting engagement with the drill steel and its flange.

4. In a rock drill, the combination with

the body of the tool, and the drill steel guided within said body, of a coiled spring concentrically secured to said body, and a locking bail on said spring adapted to be rocked into and out of locking engagement with the drill steel, the portion of the bail which embraces the drill steel being narrower at its open end than the diameter of the drill steel.

5. In a rock drill, the combination with the body of the tool, and the drill steel guided by said body, of a coiled spring on said body, and a pivoted bailed connection between the spring and steel.

In testimony that I claim the foregoing as my invention, I have signed my name in presence of two subscribing witnesses.

CHARLES CHRISTIANSEN.

Witnesses:

FRIDA KLAIBER,

PAULINA MÜLLER.
